CLAIM

The ornamental design for a CUTTER FOR FOOD PRODUCTS as shown and described.

DESCRIPTION

FIG. 1 is an isometric view of a CUTTER FOR FOOD PRODUCTS.

FIG. 2 is another isometric view of the CUTTER FOR FOOD PRODUCTS of FIG. 1.

FIG. 3 is a top plan view of the CUTTER FOR FOOD PRODUCTS of FIG. 1.

FIG. 4 is a bottom view of the CUTTER FOR FOOD PRODUCTS of FIG. 1.

FIG. 5 is a front elevation view of the CUTTER FOR FOOD PRODUCTS of FIG. 1.

FIG. 6 is a rear elevation view of the CUTTER FOR FOOD PRODUCTS of FIG. 1.

FIG. 7 is a left side elevation view of the CUTTER FOR FOOD PRODUCTS of FIG. 1.

FIG. 8 is a right side elevation view of the CUTTER FOR FOOD PRODUCTS of FIG. 1.

FIG. 9 is a cross-sectional top plan view of the CUTTER FOR FOOD PRODUCTS of FIG. 1, taken on the line 9-9 in FIG. 5.

Portions of FIGS. 1 through 9 are shown in broken lines and dash-dot-dash boundary lines illustrating portions of the article that form no part of the claimed design.

1 Claim, 6 Drawing Sheets
